(57) **CLAIM**

The ornamental design for a handheld palm cooling device as shown and described.

DESCRIPTION

FIG. 1 is a top-left front perspective view of a handheld palm cooling device in a closed configuration, showing my new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a bottom-right front view thereof;

FIG. 9 is a top-left front perspective view of a handheld palm cooling device in an open configuration;

FIG. 10 is a front view thereof;

FIG. 11 is a back view thereof;

FIG. 12 is a left view thereof;

FIG. 13 is a right view thereof;

FIG. 14 is a top view thereof;

FIG. 15 is a bottom view thereof; and,

FIG. 16 is a bottom-right front view thereof.
